UNITED STATES PATENT OFFICE.

WILLIAM J. NEWMAN, OF CHICAGO, ILLINOIS.

APPARATUS FOR REMOVING DIRT FROM EXCAVATIONS.

SPECIFICATION forming part of Letters Patent No. 764,201, dated July 5, 1904.

Application filed May 25, 1903. Serial No. 158,594. (No model.)

To all whom it may concern:

Be it known that I, WILLIAM J. NEWMAN, of Chicago, in the county of Cook and State of Illinois, have invented certain new and useful 5 Improvements in Apparatus for Removing Dirt from Excavations; and I do hereby declare that the following is a full, clear, and exact description thereof, reference being had to the accompanying drawings, and to the letters 10 of reference marked thereon, which form a part of this specification.

This invention relates to improvements in apparatus for removing dirt from excavations and conveying the same to and delivering it 15 to wagons or other vehicles by which it is removed; and the invention consists in the matters hereinafter set forth, and more particularly pointed out in the appended claims.

In the drawings, Figure 1 is a side elevation, partially in section, of an apparatus made 20 in accordance with my invention, showing the location thereof relatively to an excavation from which dirt is to be removed. Fig. 2 is a top plan view of the dumping-car and the 25 hopper and supporting structure therefor, showing the car in its dumping position. Fig. 3 is a transverse section of the car, taken on line 3 3 of Fig. 4. Fig. 4 is a side elevation 30 of the dumping-car. Fig. 5 is a central longitudinal section thereof. Fig. 6 is a partial plan view of said car. Fig. 7 is a transverse section of one of the deflector-bars.

As shown in the drawings, A A designate 35 the two rails of the track, which extend from the bottom of the excavation to a point outside thereof. Said rails are supported in the bottom of the excavation on transverse sleepers A' and on the sloping side of the excavation on inclined stringers A², as shown in Fig. 40 1. E designates a dumping-car which travels on said rails.

C designates a hopper located below the upper end of the track into which the contents of the car are dumped. The upper end of 45 the track is arranged horizontal, or approximately so, as indicated at A³, and the car is adapted to be run upon the horizontal end of the track preparatory to dumping. The upper horizontal part of the track and the hopper are supported (the latter beneath the for-

mer) on a frame structure consisting of vertical posts D D' and transverse beams or girders D² D³ D⁴, the upper ends of the track-rails being supported on the girders D⁴ and the hopper on the girders D² D³. The hopper is supported a sufficient distance above the ground-level to permit a wagon to drive thereunder to receive through the hopper the contents of the dumping-car, as clearly shown in Fig. 1. The hopper is provided across its 55 top with transverse bars c, which act to break up the load of the car when dumped into the hopper, so that said load will adapt itself readily to the vehicle-body below. The provision of said bars also render less severe the 60 shock of the weight of the load striking the body of the vehicle.

The dumping-car consists of an open-topped vehicle E, having a bottom wall E', side walls E², and a rear wall E³. The bottom of the 70 vehicle is supported on a frame consisting of longitudinal side frame members E⁴ E⁴ and transverse and frame members E⁵ E⁵. The side walls of the car are attached to vertical posts E⁶, rising from the longitudinal frame 75 members E⁴.

F designates a door which closes the front end of the car. Said door is arranged obliquely or inclined, and the front margins of the side walls of the car are inclined to afford seats 80 for the door when closed. The door extends from the bottom to the top of said side walls. The door is herein shown as carried by the forward end of a swinging frame consisting of two side members, one at each side of 85 the car, and each comprising an oblique bar F', attached at its forward end to the upper side of the door and hinged at its rear end at the rear end of the car, and a horizontal brace-bar F², attached to the rear end of said bar 90 F' and at its forward end to the lower side of the door. As herein shown, said forward ends of the frame-bars F' F² are attached to the door by means of transverse rods f f', extending loosely through said bars and through 95 cleats f² on the front face of said door. The rear ends of the bars F' of said swinging frame are pivoted or loosely connected to a transverse rod f³ at the rear of the car, which is attached at its ends in lugs f⁴, rising up- 100

wardly from rearward extensions of the frame members E¹ of the car. The door supported in this manner on the car swings on the pivot-rod f³ to open and close the same, the open position thereof being shown in dotted lines in Fig. 4.

The car is supported on front and rear traction-wheels G G', respectively, which are affixed to front and rear axles G² G³, respectively mounted in bearings g g', depending from the floor-frame of the car. Said car is drawn upwardly from the excavation on the track-rails A by means of a cable H, which is trained over pulleys H' H', affixed to the 15 hopper and track supporting structure, and is adapted to be connected with any suitable source of power, as a motor - driven drum. The cable H is attached at its rear end to two diverging chains H³ H³, which latter are attached to the forward ends of the bars F' of the swinging door-frame. As herein shown, said rear ends of the chains are attached directly to the front ends of the frame-bars F', and the chains are joined at their forward 25 ends to a ring to which the cable H is attached. It will be observed that by reason of the fact that the swinging frame for the door is pivoted to the car-frame at the rear lower part thereof and the further fact that the 30 cable is attached to the door at the upper side thereof the cable when power is exerted thereon to draw the car up the incline exerts a downward pull on the door and its frame, and therefore holds said door in its 35 lowermost or closed position.

Referring now to the devices for tilting the car to dump the contents of the same into the hopper C and from thence to a wagon below when the car reaches the upper or horizontal part of the track, these parts are made as follows: The rear axle G³ of the car is provided outside of each traction-wheel G thereof with a wheel I. Said wheels I of the rear axle are adapted to strike when the front 40 end of the car reaches the upper horizontal part of the track deflecting-bars J J, which are supported at their lower ends from the stringers A² and at their upper ends by the posts D' of the hopper and track supporting 45 frame, the deflecting-bars J being located laterally outside of the track-rails A and parallel therewith. With this construction when the car reaches the upper horizontal part of the track and the wheels I strike the deflecting-bars J the car assumes a forwardly inclined or tilted position, as shown in Fig. 1, the front end of the car being carried forwardly over the hopper C. When the car reaches this position, the door-frame and door 50 are swung upwardly, owing to the location of the cable guide-pulley H', so that the contents of the tilted car are free to be discharged therefrom. After the car has been dumped and the tension on the cable is released the 55 weight of the rear end of the car causes the

wheels I thereof to travel downwardly on the rails J until the rear traction-wheels strike the rails A, the car thereby assuming a downwardly-inclined position, in which position it is carried by gravity down the inclined track 70 to the bottom of the excavation, where it is again filled, to be thereafter drawn out of the excavation and dumped in the manner before described.

The bars J are preferably provided with 75 metal wearing-bars j, having the form of angle-irons, which embrace the corners of the bars, as shown in Fig. 1.

By the use of the apparatus described I am enabled to quickly transfer earth from excavations to a wagon or other vehicle in which the same is to be conveyed from the excavation by means not requiring the rehandling of the earth. The apparatus is simple and inexpensive in its structure and operation 85 and may be readily removed from place to place.

Certain of the structural details may be varied without departing from the spirit of my invention, and I do not wish to be limited to 90 such details except as hereinafter made the subject of specific claims.

I claim as my invention—

1. A dumping apparatus comprising a sloping track, the upper part of which is substantially horizontal, a dumping-car having traction-wheels which travel on the rails of said track, a guide-hopper located below the upper part of said track, inclined deflector-bars located laterally outside of the track-rails near the upper end thereof, parts on the sides of said car adapted to engage said deflector-bars to tilt the car when the latter reaches the upper end of the track, a door for closing the front end of the car and attached to a frame which is hinged to the car and a cable for drawing the car from the lower to the upper end of the track and attached to the upper side of the door, whereby the pull of said cable acts to hold the door closed 100 while the car is traveling up said inclined track, but pulls the door open when the car is brought to its dumping position.

2. A dumping apparatus comprising a sloping track the upper end of which is substantially horizontal, a car traveling on said track, a door for closing the front end of the car, a swinging frame to which said door is attached and pivoted at its rear end to the rear end of the car, a cable attached to the upper side of the door for drawing the car up said track and means located at the upper end of the track for tilting the car.

3. A dumping apparatus comprising a sloping track the upper end of which is substantially horizontal, a car traveling on said track, a door for closing the front end of the car, a swinging frame to which said door is attached and pivoted at its rear end to the rear end of the car, a cable attached to the upper side of 125

the door for drawing the car up said track, and means whereby the door is opened as the car is tilted.

4. A dumping apparatus comprising a sloping track, the upper end of which is substantially horizontal, a car traveling on said track, a door for closing the front end of said car, the front margins of the side walls of the car being forwardly and downwardly inclined and the door being inclined to seat against said inclined margins of the side walls, a swinging frame to which said door is attached and pivoted at the rear end of the car, a cable for drawing the car up said track which is connected with the upper side of the door and means located at the upper end of the track for tilting the car and constructed to open said door as the car is tilted.

5. A dumping apparatus comprising a sloping track, the upper end of which is substantially horizontal, a car provided with traction-wheels which travel on the rails of said track, a door which closes the front end of said car, a swinging frame to which said door is attached and which is pivoted to the rear end of the car, a cable for drawing said car upwardly on said track and connected with the upper side of said door, deflector bars or rails located laterally outside of the track - rails near the upper end thereof and wheels at the side of the car adapted to engage said deflector bars or rails.

6. A dumping apparatus comprising a sloping track, the upper part of which is substantially horizontal, a frame for supporting the

upper part of said track, a hopper supported on said frame and located below said horizontal part of the track, a car traveling on the rails of said track, a door closing the front end of said car, a swinging frame to 40 which said door is attached and pivoted at its rear end to the rear end of the car, a cable connected with the upper side of the door, a pulley at the upper end of said supporting-frame over which said cable is trained, deflector-bars located laterally outside of the track-rails near the upper end of the track and parts on the sides of the car adapted to engage said deflector-bars to tilt the car as it reaches the horizontal part of the track. 45 50

7. A dumping apparatus comprising the track-rails A having the horizontal parts A', the car E provided with traction-wheels G G' which travel on said rails, the door F for closing the front end of said car, the swinging frame attached to said door and pivoted to the rear end of the car, the cable H connected with the upper part of said door and trained over the pulley H', the deflector-bars J and the wheels I on the rear axle of the car 60 adapted to engage said deflector-bars.

In testimony that I claim the foregoing as my invention I affix my signature, in presence of two witnesses, this 9th day of April, A. D. 1903.
